UNITED STATES PATENT OFFICE.

HENRY S. BELDEN, OF CANTON, OHIO.

IMPROVEMENT IN METHODS AND MEANS OF SUPPLYING STREET-LAMPS WITH OIL.

Specification forming part of Letters Patent No. 222,856, dated December 23, 1879; application filed March 1, 1878.

To all whom it may concern:

Be it known that I, HENRY S. BELDEN, of Canton, in the county of Stark and State of Ohio, have invented certain new and useful Improvements in Processes of Supplying Street-Lamps with Oil; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention relates to various improvements in the method and means of supplying with naphtha, gasoline, or other hydrocarbon oil the lamps or lanterns employed for illuminating streets, being the improvements in the method of filling and transporting detachable cans or reservoirs of said lamps, and in such improvements in said cans or reservoirs as to make them best adapted for carrying out the process.

The ordinary method of supplying with oil the burners employed in the lamps or lanterns for lighting the streets is substantially as follows: A certain number of the lamps are put under the care of an operator, whose duty it is to attend to filling the reservoirs and to lighting and extinguishing the burners. Generally, stationary cans or reservoirs permanently attached to the burners are employed, which the operator fills by pouring into them oil from cans which he carries with him from post to post, making an especial trip for this purpose. Owing to the long time required for this filling of reservoirs the trip to supply them must be taken during the day sometime, and another trip must be taken for the purpose of lighting the burners. By the repeated fillings and emptyings along the streets oil is largely wasted, both from supplying and from exposure to the air, the volatile hydrocarbons losing very largely from such an exposure. After these stationary or permanent cans have been thus filled they are submitted during the day to the heat of the sun, which, as is now known from experience, results in a large loss of the light oils by evaporation.

Another method of supplying the lamps

with oil has been to provide them with detachable reservoirs, which could be removed from the lamps and carried to a store-house for filling; but this process was subject, as hitherto practiced, to the same objection as the one last described—viz., the great loss of time, as it required an especial trip during the day for the removal of the cans for filling and another trip for replacing the cans and lighting the burners.

By either of the methods hitherto employed at least twice the time required by my improved process and apparatus, to be hereinafter fully set forth, is consumed, and it is the object of my invention to avoid these objections, and to save the time and material ordinarily wasted in filling and lighting.

I furnish each district with the peculiarly constructed detachable cans or reservoirs, of a number greater than the lamps in said district, (preferably there are two removable cans for each lamp,) so as to avoid the necessity of making more than one trip during the day, and I provide each operator with the barrow or wagon, or other vehicle suitable, and constructed to carry safely any desired number of detachable cans in use.

I will now describe the apparatus which I have found best adapted for carrying out my system.

Figure 1 represents a vertical transverse section of the rack or case and employed in filling and transporting the detachable cans. Fig. 2 is a top-plan view of the rack. Fig. 3 is a vertical section of a vapor-burner street-lamp with my improved reservoir attached thereto.

In the drawings, A represents the body of an ordinary street-lamp; B, the burner, and B' a feed-pipe extending from the burner to the reservoir; but a detailed description of the said burner, feed-pipe burner, or street-lamp will not be needed, as they form no part of the present invention, which relates to the method and apparatus for supplying the burner with oil. The feed-pipe B' extends a short distance through the upper part of the street-lamp, and is screw-threaded at its upper end.

C represents a cup or receptacle, the bottom of which is somewhat conical in shape, and is

provided with a screw-threaded socket, C', whereby it is attached to the feed-tube B'. This socket C' extends a short distance above the bottom of the cup C, forming a trap in which to catch water, dust, or other impurities that may find access to the cup. These impurities may reach the cup through the removable reservoir, or may be driven in by the winds or rain when the detachable can is removed, or between the two vessels, even when the can is inserted in the cup.

D represents the removable can or reservoir, which in diameter is slightly less than the outer cup or receptacle, C, so as to be readily inserted therein. It is provided with an orifice, d, below the valve-seat, for the escape of the oil. The top of this can is extended outwardly and downwardly so as to form a flange, D', to project over the upper edge of the cup C when the can is inserted, and prevent, as much as possible, the entrance of impurities into the outer cup. The can D has a screw-threaded neck, d', to which is fitted a screw-threaded cap, E, which has a flaring portion, e, to prevent the access of impurities to the can.

E' represents a valve-rod constructed to extend from the exit-orifice in the bottom of the can to the cap, to which it is secured in any suitable manner, as by soldering, riveting, or by nuts. The lower end of this rod E' is beveled or so shaped as to make a perfectly tight valve.

E² is a tube extending from the aperture d to, or nearly to, the neck d', and is employed to support the valve-rod E' and to guide it to the valve-seat e², formed at the bottom of tube E².

F F represents small apertures drilled through the tube E², to permit oil to pass from the can into said tube, and thence to the feed-pipe.

The rod E' is of such length that when the cap E is firmly screwed to the neck d' the bottom of the rod shall rest tightly upon the valve-seat e². It will be seen that with a valve-rod constructed and operated as described the stop-cock ordinarily employed with other constructions to control the flow of oil between the reservoir and the burner may be dispensed with, and that a complete control of said flow of oil can be had through the removable can. The feed-pipe B' may, if desired, be provided with the usual stop-cock to regulate the passage of oil; but it will not be found necessary under most circumstances. As the aperture F is situated at some distance from the bottom of the can D, it is manifest that there will be a space from which the liquid in the can cannot flow through said aperture. This space is provided for the accommodation of the dirt, water, and other foreign matters, which, notwithstanding the greatest care used in preparing and manipulating burning-oils, are always found in them in greater or smaller quantities. In the construction shown any water, sediment, or impurities that may be present in the oil will settle by gravity to the bottom of

the can, and remain in the depression or trap below orifices F F, formed around the lower end of tube E², whence they may be removed after the oil has been consumed by turning the can upside down and allowing them to escape through the neck d'. Thus it will be seen that I provide a double security against the passage of foreign matters into the feed-pipe by furnishing the inner can with the trap, and also the receptacle C with a trap, which will arrest any impurities that might escape from the can.

G represents a rack constructed of sheet metal to hold any desired number of detachable cans during the operation of filling and transporting. It is preferably divided into compartments, each of sufficient size to hold and support one of the detachable cans. The compartments may be supported either by walls H or by rods, or by other suitable device. When walls are employed I construct them with an opening, h, at the bottom, to permit communication between the various compartments. Each row of compartments is provided with supporting ribs or projections h', attached to the bottom of the rack. These are designed to support the cans at a short distance above the bottom of rack G, so as to form a sediment-chamber below each can, in which impurities will settle and be prevented from entering the cans.

In Fig. 2 I have shown this rack G as constructed to hold twelve of the reservoirs; but it is evident that it may contain a greater or less number of compartments, if desired. After the cans are inserted in their respective compartments they are held in place by means of trap-pieces I, hinged at i at the upper side of the rack, and passing over the tops of the cans, respectively. Each may be provided with a central collar or ring, i', surrounding the neck of the can, so as to firmly hold the top of the can, and yet allow manipulation of the cap E and valve-rod E'. After the cans have been inserted they are filled at one operation by pouring oil into any one of the compartments in the rack G. The height to which the oil rises in cans may be known from its height in the rack.

H² is an exit tube or pipe extending from the wall or rack, and provided with the stop-cock H³, to permit or prevent the oils flowing from the rack. Before the oil is poured into the rack, cap E from each can is unscrewed from neck d' and the orifice d thereby opened, so that the oil can pass into the cans. After they have been filled the valve-rod is replaced in the seat e², and the cap E again screwed upon the neck d', and the orifice d is tightly closed. The filled cans are now oil-tight and ready for transportation, and to be substituted for empty cans upon the lamps. After the cans have been filled the residue of oil in the rack is withdrawn through the tube H². Outside the great saving of time that is thus effected by filling the large number of cans at one operation, it will be seen that a large part

of the water, dirt, and other foreign matters contained in the oil will be prevented from entering the cans by filling them through the bottom while they are in an upright position supported in rack G. By filling the cans separately through the top such impurities would be passed directly into the cans; but by my improved process they are caught and retained in the bottom of the rack, whence they can be removed. The racks containing reservoirs of oil are stored in a cool and suitable place until the time arrives for lighting the lamps, when they are placed in a transporting-vehicle and are taken by the operator upon his trip for lighting. While making this trip he removes in turn each empty can from its holding-cup and replaces it with a filled can from the rack. After completing the trip empty cans that are thus gathered in the racks in large numbers are carried to a common magazine or depot, where they are all filled again at one operation. Before exchanging the cans it will be found desirable to remove from the cups C any impurities that may be gathered in the trap therein, which may be conveniently done by means of a sponge. As this trap is located above the level of the burner, it will be seen that the contents of cup C will not (when reservoir D is removed) extend above the trap and interfere with readily cleansing it. The valve-rod E should be screwed tightly into the seat e^2 , so as to prevent the passage of all foreign matter from the trap in the bottom of the can into the feed-tube and burner. After the filled tank is inserted into the cup or receptacle C, oil is permitted to flow to the burner by partially unscrewing the cap E from neck d' , which lifts rod E' from seat e^2 , and allows air to enter the can above the oil. When the oil appears at the burner it is ignited and the door of the lamp is closed, after which the operation of the burner can be regulated by the cap E and rod E'.

To one practically acquainted with the operation of street-lamps it will be evident that my improved method and apparatus possess many advantages over those now employed. A far greater number of lamps may be put under the care of each operator, owing to the great saving of time in making the rounds for supplying the burners with oil. The oil supplied by the hereinbefore-described means will reach the burner clean and pure, having been subjected to several cleansing operations. The great superiority of the sediment and water trap in my detachable reservoir over the trap in a fixed reservoir, or in any of the various parts of the lamp, will be readily understood, as the reservoir can be easily cleaned by removing and inverting it, and when many of the cans have been gathered together they can all be thoroughly cleansed at one operation, thus saving much of the time consumed in sponging, wiping, or otherwise cleansing a number of fixed cans separately.

It will be further seen that my construction

of reservoir, when used in combination with a street-lamp, operates in an essentially different manner, and produces a result which is materially different from the function performed by a reservoir having a similar trap when used in combination with a portable lamp and rigidly attached to the other part of such lamp, because my improvement enables the operator to clean the reservoirs at the place of filling, which place may be quite remote from the lamp, and at such time as shall be found most convenient, whereas if the reservoir were attached rigidly to the street-lamp it would necessitate cleaning each one separately, either at the time of lighting or during the trip made for that purpose, either of which would consume a great amount of valuable time; and it is further apparent that a reservoir with a trap in the bottom open only at the top cannot be cleaned by inversion when attached rigidly to a street-lamp.

I do not, in this application, claim a detachable reservoir for street-lamps provided at the bottom with a trap to receive impurities from the oil, and an opening at the top through which such impurities may be removed by inverting the can, inasmuch as I desire to make a separate application embodying this feature of invention, and other features which I have shown in my improved reservoir, which application I propose to file at the earliest opportunity, for which reason I prefer to limit this patent to the specific features of construction embodied in the claims hereof, reserving the right to claim all other patentable matter in a subsequent application.

Having thus described my invention, what I claim as new, and desire to secure by Letters Patent, is—

1. The herein-described method or system of supplying street-lamps with oil, consisting in providing the lamps with removable reservoirs, of a number greater than the number of the lamps, and providing also a conveyance adapted to transport filled reservoirs, and, by means of these devices, removing the empty reservoirs and replacing them with filled ones, substantially as set forth.

2. In an apparatus for supplying oil to street-lamps, the combination of an oil-tight tank provided with a detachable reservoir, having an opening in the tube through which air passes out, and an opening in the bottom through which oil enters from the tank, substantially as set forth.

3. In an apparatus for supplying oil to street-lamps, the combination, with one or more detachable reservoirs, provided with openings at top and bottom, of an oil-tight tank provided at the bottom with a receptacle below the reservoir-support, adapted to collect impurities from oil with which the reservoirs are filled, substantially as set forth.

4. In combination with the filling-tank G, hinged strap-piece I, as and for the purpose set forth.

5. In combination with a lamp-burner, the fixed cup C, with an open top, and provided with a trap for impurities above the level of the burner, substantially as set forth.

6. In combination with the air-inlet and the oil-inlet, the cap E and valve rod E', rigidly attached to said cap, substantially as set forth.

7. In a lamp, a reservoir having an aperture for the inlet of air, and another aperture for outlet of oil, in combination with mechanism

for opening and closing both apertures by the same operation, substantially as and for the purpose set forth.

In testimony that I claim the foregoing as my own I affix my signature in presence of two witnesses.

HENRY S. BELDEN.
